UNITED STATES PATENT OFFICE.

HENRY A. HOUSE, OF BRIDGEPORT, CONNECTICUT.

IMPROVEMENT IN GARTERS.

Specification forming part of Letters Patent No. 136,599, dated March 11, 1873.

To all whom it may concern:

Be it known that I, HENRY A. HOUSE, of Bridgeport, in the county of Fairfield and State of Connecticut, have invented a new and Improved Spring-Garter; and I do hereby declare that the following is a full, clear, and exact description thereof, reference being had to the accompanying drawing making part of this specification, in which—

Figure 1 is a view of the garter in its normal condition. Fig. 2 is a view of the garter, showing the spring contracted. Fig. 3 shows by a section the attachment of the metal strips to the caps at the ends of the spring.

Similar letters of reference denote corresponding parts in the several figures.

This invention relates to an improvement on metallic spring-garters for ladies' wear; and has for its object the combination of flexible strips with a coiled spring in such manner that the spring acts by extension on the strips, thereby preventing the spring from being injured by stretching it, as will be hereinafter explained.

The following description of my invention will enable others skilled in the art to understand it.

In the accompanying drawing, A represents a coiled spring, which I prefer to make of the flattened form shown in the drawing, and which has caps *a a* permanently secured to its extremities. B B represent two thin metallic strips, which are passed loosely through the caps *a a* and through the spring A. One strip

is passed through one of the caps and secured permanently to the other cap, and the other spring is applied in the same way, so that in the act of elongating the garter by drawing on the strips B B the caps *a a* will approach each other and the spring will be contracted, as shown by Fig. 2. It will thus be seen that the spring operates by extension, and that it cannot, while in use, be stretched; consequently there is no liability of the spring being strained. The strips B B are made of thin metal, and they are perforated with cruciform holes *c*, which allow free ventilation of the garter, and also serve to receive the T-shaped heads *b* on the extremities of the strips in fastening together the ends of these strips around the leg.

I do not, under this application, claim a flat-spring garter; nor do I confine myself to a flat-spring garter, as it may be made of two round springs suitably connected together.

Having described my invention, what I claim is—

1. The garter-spring A, having its ends connected to internal strips B B, substantially as described.
2. The strips B B, perforated as described, and having T-shaped fastenings *b* on one or both ends, in combination with the spring A, substantially as described.

HENRY A. HOUSE.
